UNITED STATES PATENT OFFICE

2,503,343

COLLAPSIBLE EGG CARTON

Henry Levine, Philadelphia, Pa.

Application August 18, 1945, Serial No. 611,287

1 Claim. (Cl. 229—29)

1

This invention relates to cartons or containers and more particularly to an improved construction of cellular carton of the type adapted to receive eggs or other fragile articles requiring protection in the handling thereof.

Among the principal objects of the present invention is to provide a cellular carton wherein the longitudinal and transverse walls thereof are so related to each other that the assembly thereof into the form of a complete carton is effected expeditiously by a simple manual operation and without necessitating the use of any special tools or assembling devices.

In general, the carton of the present invention is constructed in accordance with the principles disclosed in my prior patent, No. 2,005,345, issued June 18, 1935, wherein a separate, readily insertable element is employed to interlock the transverse partition walls with the bottom wall of the carton in such manner as to maintain the transverse walls in parallel relation and at the same time support the bottom wall against collapse. However, the present construction differs from the prior patented construction in several important respects in order to render more facile the manufacture and manual setting-up of the carton and to provide for greater cushioning support for the eggs in the container. All of these differences in construction will be apparent from the detailed description which follows, it being understood that the present invention consists in the combination, construction, location and relative arrangement of parts, all as described hereinafter, as shown in the accompanying drawings and as finally pointed out in the appended claim.

In the accompanying drawings, Figure 1 is a view of the blank of which the side, top and bottom walls are formed;

Figure 2 is a view of the blank of which the transverse partition walls are formed;

Figure 3 is a perspective view of the complete carton expanded into shape for receiving the articles for which it is intended;

Figure 4 is a perspective view of the carton with parts thereof broken away and a portion of the top raised to show the interior construction of the carton;

Figure 5 is a bottom plan view of the carton;

Figure 6 is a transverse sectional view showing the top walls in opened position;

Figure 7 is a similar transverse sectional view showing the top walls in closed position; and

Figure 8 is a partial longitudinal sectional view taken on the line 8—8 of Figure 6.

2

The box or carton of the present invention is preferably constructed of a paper stock, such as chip board, having the inherent capacity of resiliency and of bending along predetermined lines such as are produced by a scoring operation. Such a material, which will meet the requirements of the present invention, is inexpensive and well known at the present time for the manufacture of cellular cartons or boxes.

10 Referring to the drawings, the blank 10 of Figure 1 is in the form of a single sheet scored along the parallel lines *a*, *b*, *c*, *d*, *e*, *f* and *g* to provide a plurality of foldable sections 11, 12, 13, 14, 15, 16, 17 and 18. The intermediate sections 14 and 15, which together constitute the bottom wall of the carton, are suitably stamped to provide a series of uniformly spaced slots 19 which extend equal distances to either side of the central score line *d*. In addition, the free edges of the outermost sections 11 and 12 of the blank are each slotted, as at 20, to provide a plurality of similar tab elements 21, it being noted that the side edges of each such element are respectively in line with a pair of the central slots 19, the tab element itself being in centered relation with respect to each such pair of slots.

The blank 11a of Figure 2 is suitably stamped, scored and slit to provide a plurality of partially cut out partition members 22, all but one of which are integrally anchored to the longitudinally extending side strips 23—23 by means of opposed triangularly shaped connecting elements 24. The endmost partition is anchored to the side strips by rectangular shaped connecting elements 24a, which may be, if desired, also triangularly shaped. The free ends of the partition members are so cut along the lines 25, 26, 27, 28, 29, 30 and 31 as to provide each of them with a projection 32 located centrally between a pair of oppositely sloping edge portions 33—34. Also, the cuts along the lines 25 and 31 at opposite ends of each partition member are of such arcuate shape as to provide each triangular anchor element 24 with freely extending portion 35 which may be bent downwardly out of the plane of the anchor element 24 along the score line 36. The partition members 22 are adapted to be swung into planes substantially paralleling each other and extending at right angles to the common horizontal plane of the anchor elements 24, each of these partition members being centrally provided with an opening 37 of substantially semi-circular form. Preferably, the basal portion of each such opening 37 is closed by a bendable tab portion 38 struck

out of the blank as shown for a purpose which will be apparent hereinafter.

In the carbon of the present invention the blank 10 is employed to form the bottom wall opposite sides and the top of the carton, while the blank 11^a, secured to the blank 10, as shown in Figures 4 to 7 inclusive, provides the transverse portions which divide the carton into longitudinally spaced cells.

In forming the carton, the securing strips 23-23 of the transverse partition member blank are respectively secured to the sections 13 and 16 of the blank 10 which form the opposite side walls of the carton. Preferably, the securing strips 23-23 are respectively glued or otherwise secured to the upper portions of the side wall panels 13 and 16 with the upper edges of the strips 23-23 closely adjacent the scored fold lines b and f.

With the blank 11^a secured in position between the side panels 13 and 16 of the blank 10, as shown most clearly in Figure 6, the transverse partition members of the said blank 11^a may each be rotated about their supporting gussets 24 (24^a in the case of the endmost partition member) so that all of the transverse partitions 22 assume a substantially parallel relation with the bottom projections 32 of the several transverse partition members respectively in registry with the slots 19 formed in the bottom wall sections 14-15 of the carton blank 10. These sections 14-15 which form the bottom wall of the carton are pressed upwardly, as shown in Figures 6 and 7, form a rather wide and shallow inverted V, the oppositely inclined sections 14 and 15 of the bottom wall being respectively in engagement with the inclined bottom edges 33 and 34 of the transverse partitions. In this relation of the transverse partitions with respect to the sections 14 and 15 of the bottom wall of the carton, the projections 32 of the transverse partitions extend through the slots 19 with the ridge of the bottom wall substantially coincident with the aligned openings 37 of the several partition members. This ridge of the bottom wall is, of course, coincident with the score line d of the blank 10 and is formed by pressing the sections 14 and 15 upwardly against the bottom edges of the transverse partitions 22 when the latter are rotated out of their common plane, as shown in Figure 2, into parallel relation, as shown in Figures 3 to 8 inclusive.

When the carton is expanded into the shape of the box shown in said Figures 3 to 8 inclusive, it will be observed that the sections 13 and 16 constitute the opposite side walls thereof, the sections 14 and 15 constitute the upwardly inclined portions of the bottom wall, and the sections 11-12 and 17-18 constitute the top or lid panels of the carton. In order to effect the desired and necessary interlocking relation between the transverse partition members 22 and the bottom wall sections 14-15 of the carton, a separately insertable locking strip 40 is employed, this strip being shown most clearly in Figures 3, 5 and 8 wherein it will be observed merely as a relatively narrow strip projected through the aligned openings 37 of the transverse partition members, this strip being nested between the ridge d of the bottom wall of the carton and the lower edges of the openings 37. The locking strip 40 thus serves not only to effect a positive interlock between the transverse partition members 22 and the bottom wall of the carton, but also serves effectively as a support from which the bottom sections 14 and 15 of the carton are suspended.

In order to more securely retain the interlocking

strip 40 in position against unintentional or accidental displacement, the openings 37 in the partition members are each provided as aforesaid with struck-out tab portions 38, the free edges 5 of which resiliently engage the interlocking strip as it is projected through the said openings 22 to frictionally hold the strip in place.

Referring now to the top or lid sections 11-12 and 18-17 of the carton, it will be noted that 10 the sections 11 and 18 are each bendable relatively to their adjoining sections 12 and 17 along the score lines a and g. The sections 12 and 17 are adapted to be folded about their score lines b and f respectively to lie in a substantially horizontal plane spaced above the upper edges of the transverse partition members 22 to provide a closure or lid of the carton, these lid sections 12 and 17 being held in place by means of the free marginal sections 11 and 18 which are brought 15 together and interlocked with the transverse partitions 22, as shown in Figure 7. These free marginal lid-locking sections 11 and 12 are each provided with a series of slits 20, as hereinbefore described, the several slits of the section 11 being 20 thus brought into registry with the corresponding slits of section 18 so that each pair of registry slits receives the upper edge of one of the transverse partitions 22. In order to provide for a more secure engagement between the slotted sections 11 and 18 of the top closure members of 25 the carton, the said sections 11 and 12 are each scored at opposite sides of each slit 20 thereof as at 41 to provide bendable tabs 42-42 which 30 frictionally engage opposite surfaces of the partition member. By means of this construction just 35 described, the slits 20 in the free edges of the cover sections of the carton may be narrower than the thickness of the partition members 22, the bendable tabs 42-42 on either side of the slit 40 being operative to permit the relatively thick partition member to be frictionally engaged within the slit.

It will be observed that when the cover sections 11-12 and 18-17 are bound into closed 45 position, as shown in Figure 7, the juxtaposed sections 11 and 18 thereof extend longitudinally of the carton and are disposed in the vertical median plane thereof, this plane being common with that of the longitudinally extending ridge 50 d of the bottom wall of the carton. The sections 11 and 18 thus serve as a longitudinal divider for the carton to provide the same with two rows of cells separated from each other by the transverse partition members 22, each cell being of 55 a size and shape suitable for reception of an egg or other such article.

It will be observed that the anchoring gussets 24 for the transverse partition members are each provided with freely extending bendable portions 60 35, as described aforesaid. These portions 35 normally project toward the center of each cell of the carton and serve as cushioning elements for the egg disposed in the cell, each such element engaging a side of the egg to help maintain it 65 in upright position.

An important advantage of a carton constructed as hereinbefore described and as shown in the accompanying drawings resides in the fact that when the carton is to be shipped or stored 70 and the conservation of space becomes an important factor, it may be compressed into a substantially flat shape upon removal of the interlocking strip 40 and disengagement of the partition members 22 from the bottom wall sections 75 14 and 15. In such case, the partition members

22 are all disposed in a flat plane common to that of their anchoring gussets, and the carton may then be folded flat about either of the score lines c or e. If folded flat about the score line c the sections 11, 12 and 13 are extended flatwise to overlie the flattened sections 14, 15, 16, 17 and 18 with the transverse partitions 22 disposed between these flattened outer sections of the carton. Similarly, the carton may be folded flat about the score line e, in which case the flattened sections 16, 17 and 18 overlie the flattened sections 15, 14, 13, 12 and 11 with the partitions again interposed between such flattened sections of the collapsed carton.

In order to expand the collapsed carton into shape, it is merely necessary to position the panels 13 and 16 into substantially parallel relation with the sections 14 and 15 stretched into substantially horizontal position and then rotate the partition members 22 so as to present their projections 32 respectively into registry with the slots 19. The bottom wall sections 14 and 15 are then pressed upwardly, as shown in Figure 6, and the interlocking strip 40 is thus projected longitudinally through the openings 37 and beneath the ridge d bottom wall of the carton. It will be understood, of course, that this invention is susceptible of various changes and modifications which may be made from time to time without departing from the real spirit or general principles thereof and it is accordingly intended to claim the same broadly, as well as specifically, as indicated by the appended claim.

What is claimed as new and useful is:

A carton of the character described having side

walls and an interconnecting bottom wall of inverted V-shape, the ridge of said bottom wall being provided with a plurality of longitudinally spaced slots therein, a plurality of transverse partitions hingedly secured at opposite corners thereof to the side walls of the carton and adapted to be swung into parallel relation for respective projection of their free edges through the slots aforesaid, said partitions being each provided in its free edge with a partially struck-out tab disposed immediately below the ridge of the bottom wall, and a longitudinally extending member projecting through the slits formed by said struck-out tabs to interlock the partitions and the bottom wall of the carton, said tabs serving to resiliently urge said member into frictional engagement with the ridge of said bottom wall.

HENRY LEVINE.
